UNITED STATES PATENT OFFICE.

JOSEPH BRZOZOWSKI, OF WILKES-BARRE, PENNSYLVANIA.

MOTOR FAN.

1,426,256.

Specification of Letters Patent. Patented Aug. 15, 1922.

Application filed August 4, 1921. Serial No. 489,751.

To all whom it may concern:

Be it known that I, JOSEPH BRZOZOWSKI, a citizen of Poland, residing at Wilkes-Barre, in the county of Luzerne and State of Pennsylvania, have invented certain new and useful Improvements in Motor Fans, of which the following is a specification.

The primary object of the present invention is the provision of a spring motor for air circulating fans and an arrangement for easily and quickly starting and stopping the operation of the device.

A further object of the invention is to provide an easy and inexpensive means for starting and stopping a fan motor without utilizing the mechanism by sudden strains, the device providing for the gradual stopping of the motor which is thereafter readily started by releasing the stopping mechanism.

With these general objects in view and others that will appear as the nature of the invention is better understood, the same consists in the novel construction, combination and arrangement of parts hereinafter more fully described, illustrated in the accompanying drawings, and pointed out in the appended claims.

In the drawings forming a part of this application and in which like designating characters refer to corresponding parts throughout the several views—

Figure 1 is a front elevation of a motor fan provided with my invention,

Figure 2 is a side elevation thereof,

Figure 3 is an enlarged vertical sectional view taken upon line III—III of Figure 2,

Figure 4 is a rear elevation of the upper portion of the stand and the casing shown in Figure 2,

Figure 5 is a top plan view of the motor removed from the casing, and

Figure 6 is a perspective view of the stopping and starting mechanism detached.

Referring more in detail to the drawings, my stopping and starting mechanism is preferably employed with a spring motor such as 10 herein illustrated mounted within a chamber 11 in the upper end of a standard 12 and in a casing portion or head 13 at the top of said standard. A circular plate 14 closes the rear side of the casing 13 while the power shaft 15 of the motor 10 projects through the front side 16 of said casing and is provided with a usual form of air circulating fan 17 while a wire guard 18 encircles

the fan and is attached by screws 19 to the outer surface of the head 13. The motor 10 is seated upon and suitably secured to the bottom 20 of the chamber 11.

The motor 10 includes a coil spring 21 having one end anchored as at 22 and its opposite end secured to a shaft 23 carried by the motor frame and having a squared extension 24 projecting through an opening 25 in the cap 14 for the purpose of rewinding the motor spring 21.

A gear 26 upon the shaft 23 meshes with a toothed hub 27 of a gear 28 which in turn meshes with a toothed gear 29 upon a shaft 30 while a gear 31 upon the shaft 30 meshes with a toothed hub 32 of a gear 33, the last named gear meshing with a toothed portion 34 of the fan shaft 15.

It will be understood that when the spring 21 is wound by means of a key turning the shaft 23, the release of the spring 21 causes the train of gears to operate in the usual manner, a spring motor fan turning the shaft 15 upon the outer end of which the fan 17 is secured. The fan 17 will then continue to turn until the motor has run down or its operation is in some manner interrupted. The shaft 15 is also provided with a regulator 35 of the usual construction employed with spring motors.

A shaft 36 is transversely journaled through the frame of the motor 10 and is provided with a stop hook 37 projecting therefrom with a triangular inwardly projecting end 38 adapted for engaging between the teeth of the gear 31 and stopping rotation thereof when the shaft 36 is turned to the limit of its movement in one direction. A brake wire 39 projects from the shaft 36 at a different angle from the stop hook 37 and has an inwardly turned end 40 adapted for frictionally engaging the adjacent side of the gear 33 and acting as a brake for gradually retarding the turning of said gear. An angular shifting lever 41 projects from the shaft 36 through an arcuate slot 42 in the rear plate 14 whereby the hook end 38 and wire end 40 may be brought into simultaneous engagement with the gears 31 and 33 respectively for stopping the operation of the device. A partial return rotation of the shaft 36 by means of the lever 41 simultaneously releases said hook and brake wire thereby permitting the spring 21 to continue turning the fan 17. Both of the end members 38 and 40 are nor-

mainly out of engagement with the gears 31 and 33 respectively and upon moving the lever 41 for stopping the operation of the device, the brake wire end 40 engages the 5 side of the gear 33 for retarding the movement of the device prior to the engagement of the end 38 with the teeth 31, entirely stopping the turning of the gears.

The complete operation of the device will 10 be fully understood from this detailed description thereof, the starting of the motor being the opposite operation from that of stopping the same, the stop hook end 38 being disengaged from the gear 31 15 prior to the frictional release of the brake wire 40 and whereby the motor is gradually permitted to start its operations similar to the gradual stopping of the motor heretofore fully explained.

20 The standard 12 is mounted upon any suitable base such as 43 and while the form of the invention herein shown and described is what is believed to be the preferred embodiment thereof, it is nevertheless to be 25 understood that various forms, modifications and arrangements of the parts may be made without departing from the spirit and scope of the invention as claimed.

I claim:—

30 1. A spring motor for fans including a spring and a plurality of train of gears operatively connected thereto, a transverse shaft adjacent said gears, a stop hook projecting from said shaft with an angular 35 end portion adapted for engaging between the shaft of one of said gears, a brake wire projecting from said shaft at a different angle from the stop hook with an angular end portion adapted for frictionally engaging another one of said gears during the 40 stopping operation.

2. A spring motor for fans including a spring and a plurality of train of gears operatively connected thereto, a transverse shaft adjacent said gears, a stop hook projecting from said shaft with an angular end portion adapted for engaging between the teeth of one of said gears, a brake wire projecting from said shaft at a different angle from the stop hook with an angular end 50 portion adapted for frictionally engaging another one of said gears prior to the engagement of the stop hook with the other gear, and an angular lever projecting from said shaft whereby the shaft is adapted for 55 partial rotation in opposite directions during the starting and stopping operation.

3. In a spring motor having gears, a transverse shaft journaled in parallelism with the axes of said gears, an angular 60 lever projecting from the shaft adapted for imparting partial rotation to the shaft, a stop hook and brake wire projecting at different angles from said shaft adapted for engagement with and release from adjacently positioned gears, whereby the starting and stopping of the motor is effected 65 at will.

4. In a motor having spaced gears, adjacent shafts upon which said gears are 70 mounted, a partially rotatable member transversely journaled parallel to said shafts, a stop hook and brake wire projecting at different angles from said rotatable member with the brake wire in advance 75 of the stop hook adapted for frictionally engaging the side of one of said gears prior to the engagement of the stop hook with the teeth of the other gear and turning means for said rotatable member.

In testimony whereof I affix my signature.
JOSEPH BRZOZOWSKI.
